H. E. HOLMES.
COVER FOR UTENSILS.
APPLICATION FILED DEC. 28, 1912.

Patented Sept. 8, 1914.

UNITED STATES PATENT OFFICE.

HOMER E. HOLMES, OF BURLINGTON, VERMONT.

COVER FOR UTENSILS.

1,109,990.

Specification of Letters Patent. Patented Sept. 8, 1914.

Application filed December 28, 1912. Serial No. 739,140.

To all whom it may concern:

Be it known that I, HOMER E. HOLMES, a citizen of the United States, residing at Burlington, in the county of Chittenden and State of Vermont, have invented certain new and useful Improvements in Covers for Utensils, of which the following is a specification, reference being had therein to the accompanying drawing.

10 My invention relates to improvements in covers for utensils, and has for its object to provide a device of this class which may be readily adjusted to vessels of various sizes, and which may be readily and effectively 15 sustained upon the said vessel.

Another object of my invention is to provide a device of this class constructed of a single piece of suitable flexible material, the same comprising a disk having a radial slit 20 running from the center to the edge thereof, one of the surfaces adjacent the said slotted portion adapted to fit over the second portion so that the two slotted portions upon 25 relative rotation will be moved one upon the other to be brought into the form of a cone and having means whereby this adjustment may be effectively accomplished and also means whereby the cover may be held in the adjusted position.

30 Another object of my invention is to provide a simple, cheap and effective cover of this character which can be more readily adjusted and held in its adjusted position.

In the accompanying drawings—Figure 1 is a perspective view of a utensil showing my improved cover applied thereto. Fig. 2 is a top plan view of a cover, showing it rotated so as to form a cover of less diameter than that shown in Fig. 1. Fig. 3 is a vertical sectional view taken on the line 3—3 of Fig. 2, showing the means for holding the cover in its rotated position. Fig. 4 is an enlarged plan view broken away showing the rivet in section.

45 Referring now to the drawings, 1 represents my improved cover which, as shown, is constructed of a single piece of flexible metal, the same being in the form of a disk, as clearly illustrated in Fig. 2 of the drawings. The disk at the center is provided with a central opening 2 and running from said opening radially to the edge of the disk is a slit 3, so as to form what may be termed the overlying edge or portion 4 and the underlying edge or portion 5. Within the cen-

tral opening 2 of the cover is a rivet 6, having a washer 7, above and a washer 8 below to close the said opening to prevent the escape of steam or heat from the utensil when applied thereto. The overlying portion 4, 60 adjacent the edge is provided with a handle 9, by means of which the cover is removed or placed upon the utensil, and also by means of which it is rotated, as will be hereinafter more fully described.

65 In order to limit the rotation of the overlying portion 4, on the underlying portion 5, the said underlying portion is provided with a stop 10, which is adapted to engage the edge of the overlying portion and thus limit 70 the rotation of the two portions, one upon the other. The stop 10 also serves as a means whereby the underlying portion 5 may be rotated toward the overlying portion 4, by taking hold of the stop 10 in one 75 hand and the handle 9 in the other hand, as will be readily understood. The overlying portion 4, below the handle, is provided with a pivot 11, upon which is rotatably mounted a cam 12, placed a slight distance from the 80 edge of the overlying portion 4. Between the inner face of the cam 12 and the outer face of the overlying portion 4 is placed a curved clamping member 13, said clamping member having a slot 14 through which the 85 pivot 11 passes. The upper end 14 of the clamping member is bent outwardly and slightly downwardly and forming a surface against which the cam 12 engages and slides the clamping member upwardly. The lower edge 15 of the clamping member is bent around the outer periphery of the overlying and underlying portions 4 and 5 of the disk, and when the said clamping member is 90 forced upwardly by the cam, the underlying 95 and overlying portions 4 and 5 are clamped together and the same are held in their adjusted position to form covers of different sizes. The periphery of the overlying portion adjacent the edge is cut-away, as indicated at 15, to allow the clamping member to more firmly engage the underlying portion, and the end of said cut-away portion forming a stop to engage the clamping member to limit the movement of the clamping member thereon.

100 While I have shown and described the stop 10 and also the handle 9 made of metal, it will be understood that it may be preferable to make the same of some insulated ma- 105

terial, whereby the cover may be more readily handled when hot or more readily adjusted, as will be clearly understood.

While I have shown and described a specific form of clamping member, it will be readily understood that this could be varied without departing from my invention.

Having thus described my invention, what I claim and desire to secure by Letters Patent is:

1. A cover for the purpose described, comprising a flexible disk having a slit extending from the center of the periphery thereof, one of the portions of the disk formed by the slit adapted to overlap the other portion, a cam pivotally mounted on the overlying portion, a clamping member between the cam and the overlying portion and having a slot through which the pivot of the cam passes, the upper end of the clamping member turned outwardly to form a cam-engaging surface, and the lower end of the said member turned inwardly upon the inner face of the underlying portion, whereby the overlying and underlying portions are clamped in their adjusted position.

2. A cover for the purpose described, comprising a flexible disk having a slit extending from the center to the periphery thereof,

one of the portions of the disk formed by the slit adapted to overlap the other portion, a cam pivotally mounted on the overlying portion, a clamping member between the cam and the overlying portion and having a slot through which the pivot of the cam passes, and a lateral extension against which the cam surface engages and the lower end of the said member turned inwardly upon the inner face of the underlying portion.

3. A cover for the purpose described, comprising a flexible disk having a slit extending from the center to the periphery thereof, one of the portions of the disk formed by the slit adapted to overlap the other portion, a cam pivotally mounted on the overlying portion, a clamping member between the cam and the overlying portion and having a slot through which the pivot of the cam passes and said clamping member having an inwardly turned lower end engaging the inner face of the underlying portion, substantially as shown and described.

In testimony whereof I hereunto affix my signature in the presence of two witnesses.

HOMER E. HOLMES.

Witnesses:

CHARLES E. ALLEN,
A. W. SOULE.
